D. H. Peavey, INVENTOR.

BY

Geo. P. Kimmel, ATTORNEY.

UNITED STATES PATENT OFFICE.

DAVID H. PEAVEY, OF BREWER, MAINE.

SPURRED PICKEROON.

Application filed March 27, 1925. Serial No. 18,851.

To all whom it may concern:

Be it known that I, DAVID H. PEAVEY, a citizen of the United States, residing at Brewer, in the county of Penobscot and

5 State of Maine, have invented certain new and useful Improvements in Spurred Pickeroons, of which the following is a specification.

This invention relates to a spurred pickeroon for use in handling pulp wood, and has 10 for its object to provide, in a manner as hereinafter set forth, a pickeroon having means whereby the pulp wood can be pushed or pulled, under such conditions materially expediting the handling of a length of pulp 15 wood when occasion requires.

Further objects of the invention are to provide, in a manner as hereinafter set forth, a spurred pickeroon, which is simple in its 20 construction and arrangement, strong, durable, compact, thoroughly efficient and convenient in its use, readily assembled, and comparatively inexpensive to manufacture.

With the foregoing and other objects in 25 view, the invention consists of the novel construction, combination and arrangement of parts, as hereinafter more specifically described and illustrated in the accompanying drawings, wherein is shown an embodiment 30 of the invention, but it is to be understood that changes, variations and modifications can be resorted to which come within the scope of the claims hereunto appended.

In the drawings wherein like reference 35 characters denote corresponding parts throughout the several views:—

Figure 1 is a side elevation of a spurred pickeroon, in accordance with this invention.

40 Figure 2 is a fragmentary view, in side elevation, upon an enlarged scale, of a spurred pickeroon in accordance with this invention.

Figure 3 is a fragmentary view looking 45 towards the rear side of the pickeroon.

Figure 4 is an inverted plan view of the spurred pickeroon.

A spurred pickeroon, in accordance with 50 this invention, comprises a handle member referred to generally by the reference character 1, and a head referred to generally by the reference character 2, and which is mounted on one end of the handle member 1, the latter being of the desired length and 55 provided with a gripping portion 3 and a wedge-shaped entering portion 4, which is

mounted in the head 2 and secured therein by a headed wedge 4' engaging therein and abutting against the outer side edge of the head 2. 60

The head 2 comprises a wedge-shaped body portion 5 formed therethrough with an opening 6 providing what may be termed a wedge-shaped socket for the entering portion 4 of the handle member 1. The rear end 65 7 of the body portion 5 is of greater width than the forward end 8 thereof. The body portion 5 is of a length materially greater than its greatest width, and increases in width from its forward towards its rear 70 end.

Formed integral with the forward end 8 of the body portion 5 is a pick point 9 of substantial length, having its upper edge 10 inclining downwardly with respect to the 75 upper edge 11 of the body portion 5. The lower edge 12 of the point 9 inclines slightly downwardly with respect to the body portion 5 but the inclination is not as great as the inclination of the upper edge 10. 80 The edges 10 and 11 merge into each other to provide a point 13. By constructing the picking point 9 in the manner as stated, it tapers in a direction forwardly from the forward end of the body portion 5, extends 85 laterally in a forward direction from and is disposed at right angles with respect to the head 2.

Formed integral with the rear end 7 of the body portion 5 is a laterally extending base 90 14 for a tapered spur 15 which is offset with respect to the body portion 5 and projects beyond the head of the wedge 4' which is extended into the handle member 1, or in other words, the spur 15 projects beyond the outer 95 side or top edge 11 of the body portion 5 and furthermore is disposed at an inclination with respect thereto. The base 14 is formed integral with the outer portion of the rear end of the head 2 and gradually increases in 100 width towards the outer side or top edge 11 of the body portion 5. The base 14 is arcuate in cross section and has its forward end opposing the outer side or top edge of the body portion 5. 105

The pick point 9 is disposed substantially at right angles and the spur 15 at an acute angle with respect to the handle member 1. The spur 15 is of materially less length than the length of the pick point 9. 110

The providing of the head 2 with the pick point 9 and the spur 15 enables a pulling

and pushing action to be had on a length of pulp wood, under such conditions expediting the handling thereof, or in other words, a pickeroon is set up which when used can be 5 employed for either pulling or pushing the pulp wood.

It is thought that the many advantages of a spurred pickeroon, in accordance with this invention, can be readily understood, and although 10 the preferred embodiment of the invention is as illustrated and described, yet it is to be understood that changes in the details of construction can be had which will fall within the scope of the invention as 15 claimed.

What I claim is:—

1. An implement for the purpose set forth comprising a hollow wedge-shaped head adapted to be mounted on one end of a handle member, a one-piece laterally extending tapered pick point having its inner end integral with the forward end of and flush with the outer and inner sides of said head, said point inclining slightly towards the inner side of the head, a laterally extending spur base integral with the rear end of said head at the outer portion thereof, and a tapered spur integral with the forward side of said base and offset with respect to and 25 projecting beyond the outer side of the head, said spur disposed at a slight outward inclination with respect to the vertical axis of the head.

2. An implement for the purpose set forth comprising a hollow wedge-shaped head, a handle member having its forward end mounted in said head, a one-piece laterally extending tapered pick point having its inner end integral with the forward end of and flush with the outer and inner sides of said head, said point inclining slightly towards the inner side of the head, a laterally extending spur base integral with the rear end of the head at the outer side thereof, a tapered spur integral with the forward side of said base and offset with respect to and projecting beyond the outer side of the head, said spur disposed at a slight outward inclination with respect to the longitudinal 40 axis of the handle, and means engaging in said member and abutting against the outer side of the head for connecting the latter and said member together.

3. An implement for the purpose set forth comprising a hollow head, a handle member having its forward end mounted in said

head, a laterally extending tapered pick point integral with the forward end of said head, a laterally extending spur base integral with the rear end of the head at the outer portion thereof, said base tapering towards the outer side of the head and arcuate in cross section, and a tapered spur integral with the forward side of the base, spaced from and projecting beyond the outer side of the head, said spur disposed at a slight outward inclination with respect to the longitudinal axis of the handle member.

4. An implement for the purpose set forth comprising a hollow head, a handle member having its forward end mounted in said head, a laterally extending tapered pick point integral with the forward end of said head, a laterally extending spur base integral with the rear end of the head at the outer portion thereof, said base tapering towards the outer side of the head and arcuate in cross section, a tapered spur integral with the forward side of the base, spaced laterally from and projecting beyond the outer side of the head, said spur disposed at a slight outward inclination with respect to the longitudinal axis of the handle member, and means engaging in said member and abutting against the outer side of the head for connecting the latter and member together.

5. An implement for the purpose set forth comprising a head having its outer end of greater width than its rear end, said head formed with a wedge-shaped opening for the reception of the forward end of a handle member, a laterally extending tapered pick point integral with the forward end of said head and inclining slightly towards the inner side of the head, a laterally extending spur base integral with the rear end of said head at the outer portion thereof, said base gradually increasing in width towards the outer side of the head and further arcuate in transverse section, the forward end of said base opposing the outer side of said head, and a spur integral with the forward end of the base, spaced laterally from and projecting beyond the outer side of the head, said spur disposed at a slight outward inclination with respect to the vertical axis of the head.

In testimony whereof, I affix my signature hereto.

DAVID H. PEAVEY.
